UNITED STATES PATENT OFFICE.

CARL RASMUSSEN, OF BRUNSWICK, GERMANY.

CALCULATING-MACHINE.

1,100,689.

Specification of Letters Patent. Patented June 16, 1914.

Application filed February 17, 1914. Serial No. 819,224.

To all whom it may concern:

Be it known that I, CARL RASMUSSEN, engineer, subject of the King of Norway, residing at Brunswick, Germany, have invented certain new and useful Improvements 5 in Calculating-Machines, of which the following is a specification.

My invention relates to improvements in calculating machines, and more particularly 10 in calculating machines of the class in which the setting mechanism consists of setting disks each of which is provided with nine teeth representing the values to be set on the disks and of cam disks for setting the 15 desired number of teeth into operative positions, so that when rotating the setting disks the number corresponding to the shifted teeth is transmitted to a registering mechanism. In machines of this class the 20 carrying mechanism consists of additional teeth provided on the setting disks and adapted to be shifted into operative position by means of rocking levers or hammers adapted to be operated by the numeral 25 wheels. The additional teeth provided on the setting disks for performing the carrying operations are thrown into or out of operative positions either by shifting the same in radial direction or by rocking the 30 same laterally by means of the said rocking hammers, which for this purpose are equipped with cam faces adapted when in operative positions to be engaged by the carrying teeth. Carrying mechanisms of this 35 type are shown in the patent of the United States No. 928,083, granted to Franz Trinks July 13th, 1909.

In the setting disk of the second order 40 two carrying teeth must be provided one for right hand and the other one for left hand operation of the setting disk, and the teeth must be disposed at such a distance from the main or value teeth, that when rotating the setting disks at first the rocking member or 45 hammer is rocked into operative position, and that thereafter the carrying tooth gets into engagement with the cam face provided thereon, and as two carrying teeth are provided on the setting disk the circumference of the setting disks is increased by 50 the double path of the disk required for this operation. Furthermore the carrying teeth of the consecutive setting disks must be placed relatively to each other in such a 55 way, that each time the carrying tooth of

one disk is advanced relatively to the tooth of the setting disk of the next lower order a distance corresponding to the pitch of the value teeth of the setting disks, because the carrying tooth of a setting disk can not be 60 brought into engagement with the cam face of the coöperating rocker or hammer, before the carrying tooth of the setting disk of the lower order is out of engagement with the coöperating numeral wheel or intermediate 65 gear wheel, and the rocker or hammer has been completely set in operative position. If the said distances are less than what has been described, it may happen, that the carrying teeth are not engaged any more by the 70 hammers which have been rocked too late, and therefore remain inoperative, so that they are pressed from the side against the teeth of the adjacent numeral wheel or intermediate gear wheel instead of getting into 75 engagement therewith. By thus displacing the carrying teeth relatively to each other the circumference and the diameter of the setting disks are increased, which is objectionable because thereby the said disks are 80 in a higher degree liable to be overthrown.

The object of the improvements is to provide a carrying mechanism in which the circumference and the diameter of the setting disks are comparatively small.

With this object in view my invention consists in so constructing the carrying mechanism that the carrying levers are constantly located with their cam faces at the rear of lateral noses of the radially shiftable 90 carrying teeth, so that the carrying teeth can be shifted outward and into carrying position when they have already arrived in position for engagement with the coöperating intermediate gear wheels. Furthermore it 95 is not necessary in this construction, that the carrying teeth of the setting disks of the second order are disposed a greater distance away from the shiftable teeth, but they can be disposed immediately adjacent to the said teeth. Thereby the diameter of the setting disks is materially reduced, without interfering with the proper operation of the carrying mechanism.

For the purpose of explaining the invention an example embodying the same has been shown in the accompanying drawings, in which the same letters of reference have been used in all the views to indicate corresponding parts.

In said drawings Figure 1, is a front view of the calculating machine partly in section and with a part of the cover of the casing removed, Fig. 2, is a cross-section taken on the line 2--2 of Fig. 1, Fig. 3, is a cross-section taken on the line 3--3 of Fig. 1, and Fig. 4, is a partial plan view of Fig. 3.

Referring to the example illustrated in the drawings the setting mechanism consists of setting disks a which are keyed to a shaft q adapted to be rotated from a crank q^1 through the intermediary of gear wheels q^2 and q^3 . Each of the setting disks is provided with nine radially shiftable value teeth b which are adapted to be shifted into or out of operative positions by means of a cam disk a^1 . When shifted beyond the circumference of the setting disks the said teeth engage in intermediate gear wheels n which are in engagement with gear wheels h^2 connected with numeral wheels h . The wheels n , h , and h^2 are mounted on a carriage h^3 which is adapted to be shifted in a direction parallel to the axis q of the setting mechanism. On the said carriage a revolutions counting mechanism q^4 is mounted which is located at the left hand side of the registering mechanism, and which is operated from the shaft q by means of a single tooth q^5 . The registering mechanism as well as the revolutions counting mechanism are provided with resetting devices of known construction which are adapted to be operated respectively by wing nuts h^4 and q^6 .

At the beginning and at the end of the series of value teeth b the setting disks are equipped with carrying teeth d which are likewise shiftable in radial direction. At the parts of the said carrying teeth which project beyond the circumferences of the setting disks the said carrying teeth are provided with laterally projecting noses d' , as is best shown in Fig. 1, and at the rear of the said noses cams g are provided which are in the same planes therewith. In the example shown in the figures the said cams are mounted at the sides of arms h' of levers h having rocking supports on a shaft z , the arms of the said levers being controlled by cams h' formed on the numeral wheels h . The cams h' are adapted to engage the rocking levers h when the numeral wheels pass from their nine positions to the zero positions or vice versa, and if a lever is thus rocked the arm h' is removed away from the circumference of the setting disk a and into such a position, that when turning the setting disk a the corresponding carrying tooth d is drawn out by means of its nose d' into position for engagement with the coöperating intermediate gear wheel n so as to advance the same a distance corresponding to one value. As the levers h , h' are not always rocked at the moment

when the carrying teeth d pass the coöperating cams, and the cams h' release the arms h of the rocking levers h , h' after rocking the same, means are provided for holding the rocking levers h , h' in operative positions relatively to the carrying teeth which means consists in the example shown in the figures of locking pawls o adapted to engage with noses o' at the rear of shoulders h'' of the levers h . Thereby the levers h , h' and their cams g are locked, until the setting disks a have performed a complete revolution. Between arms o'' of the pawls o and the arms h of the rocking levers h springs f are interposed which tend to return the rocking levers h , h' into normal positions and to hold the noses o' and shoulders h'' in engagement with each other.

At the end of the rotation of the setting disks a all the rocking levers h , h' which have been set for performing carrying operations are returned into normal positions by a suitable mechanism which is common to all the rocking levers. In the example shown in the figures the said mechanism consists of a disk r secured to the main shaft q and formed with a cam groove r' engaged by a pin s of a bell crank lever u having a rocking support on a fixed pivot t . The bell crank lever u is connected by a link v to an arm w secured to a rock shaft x . The shaft carries a rod or a suitable number of individual arms y which are in position for engagement with the pawls o .

In the drawings the cam groove r is shown in the position relatively to the pin s in which the setting disks are in their normal or inoperative positions, and in which the machine crank q^1 is locked. From the point of the groove which is engaged by the pin the cam groove rises at both sides and in each direction of rotation of the setting disks, and the rising branches are followed at both sides by descending branches, so that directly at the beginning of the rotation and immediately before the end thereof the pawls o are released. To retract the carrying teeth d at the end of each carrying operation into inoperative positions springs z are provided. The cam disks a^1 are connected with spur gears a^2 the teeth of which are in mesh with the teeth of gear wheels a^3 . The latter are in engagement with gear wheels a^4 which are connected with indicating disks a^5 . The latter are provided for indicating the positions of the cam disks a and the numbers set on the setting disks through peep holes a^6 as will be understood from an inspection of Figs. 1 and 2.

I claim herein as my invention:

1. In a calculating machine, the combination with the registering mechanism, and the setting mechanism comprising setting disks provided with radially shiftable teeth

- representing the values to be transmitted to the registering mechanism and radially shiftable carrying teeth having laterally projecting noses, of cams adapted to engage said noses so as to shift the carrying teeth into operative positions and located in their inoperative positions within the circular paths described by the noses, and means controlled by the registering mechanism to shift said cams into position for engagement with the noses. 5
2. In a calculating machine, the combination with the registering mechanism, and the setting mechanism comprising setting disks provided with radially shiftable teeth representing the values to be transmitted to the registering mechanism and radially shiftable carrying teeth having laterally projecting noses, of cams adapted to engage said noses so as to shift the carrying teeth into operative positions and located in their inoperative positions within the circular paths described by the noses, means controlled by the registering mechanism to shift said cams into positions for engagement with the noses, and means operative while the setting mechanism is being rotated to lock the said cams in operative positions. 10
- 25 3. In a calculating machine, the combination with the registering mechanism, and the setting mechanism comprising setting disks provided with radially shiftable teeth representing the values to be transmitted to the registering mechanism and radially shiftable carrying teeth having laterally projecting noses, of cams adapted to engage said noses so as to shift the carrying teeth into operative positions and located in their inoperative positions within the circular paths described by the noses, bell crank levers carrying said cams and under control by the numeral wheels of the registering mechanism, locking pawls provided for locking the bell crank levers in rocked positions, and means operative at the end of the operation of the setting mechanism to throw the pawls out of locking engagement with the bell crank levers. 40
- 45 4. In a calculating machine, the combination with the registering mechanism, and the setting mechanism comprising setting disks provided with radially shiftable teeth representing the values to be transmitted to the registering mechanism and radially shiftable carrying teeth having laterally projecting noses, of cams adapted to engage said noses so as to shift the carrying teeth into operative positions and located in their inoperative positions within the circular paths described by the noses, bell crank levers carrying said cams and under control by the numeral wheels of the registering mechanism, locking pawls provided for locking the bell crank levers in rocked 50
- 55 60 65 70 75 80 85 90 95 100 105 110 115 120 125 130
- positions, a spring interposed between each of the bell crank levers and co-operating pawl and tending to return the bell crank levers into normal positions and to hold the pawls in position for locking engagement with the bell crank levers, and means operative at the end of the operation of the setting mechanism to throw the pawls out of locking engagement with the bell crank levers. 75
5. In a calculating machine, the combination with the registering mechanism, and the setting mechanism comprising setting disks provided with radially shiftable teeth representing the values to be transmitted to the registering mechanism and radially shiftable carrying teeth having laterally projecting noses, of cams adapted to engage said noses so as to shift the carrying teeth into operative positions and located in their inoperative positions within the circular paths described by the noses, means controlled by the registering mechanism to shift said cams into positions for engagement with the noses, means operative while the setting mechanism is being rotated to lock the said cams in operative positions, means common to all the locking means to throw the same out of operation. 85
6. In a calculating machine, the combination with the registering mechanism, and the setting mechanism comprising setting disks provided with radially shiftable teeth representing the values to be transmitted to the registering mechanism and radially shiftable carrying teeth having laterally projecting noses, of cams adapted to engage said noses so as to shift the carrying teeth into operative positions and located in their inoperative positions within the circular paths described by the noses, means controlled by the registering mechanism to shift said cams into positions for engagement with the noses, means operative while the setting mechanism is being rotated to lock the said cams in operative positions, a cam disk connected with the setting mechanism, and an operative connection between the cam disk and all the locking pawls and adapted to throw the said pawls out of locking position. 100
7. In a calculating machine, the combination with the registering mechanism, and the setting mechanism comprising setting disks provided with radially shiftable teeth representing the values to be transmitted to the registering mechanism and radially shiftable carrying teeth having laterally projecting noses, of cams adapted to engage said noses so as to shift the carrying teeth into operative positions and located in their inoperative positions within the circular paths described by the noses, means controlled by the registering mechanism to shift said cams into positions for engagement 120
- 125 130

with the noses, means operative while the setting mechanism is being rotated to lock the said cams in operative positions, a cam disk connected with the setting mechanism, and an operative connection between the cam disk and all the locking pawls and adapted to throw the said pawls out of locking positions, said cam disk having adjacent abrupt cam faces between which the 10 operative connection engages when the

setting mechanism is in normal or inoperative position.

In testimony whereof I have hereunto set my hand in presence of two subscribing witnesses.
